JOHANN MAHLER, OF AUGSBURG, GERMANY, ASSIGNOR TO THE FIRM: MASCHINEN-FABRIK AUGSBURG-NUERNBERG, AKTIENGESELLSCHAFT, OF AUGSBURG, GERMANY, A CORPORATION OF GERMANY

INJECTION PIPING FOR INTERNAL-COMBUSTION ENGINES WITH SOLID-FUEL INJECTION

Application filed April 11, 1925, Serial No. 22,375, and in Germany May 24, 1924.

In internal combustion engines operating with solid fuel injection and which are governed by a relief valve, and in which the delivery valve is fitted in the injection piping, this 5 delivery valve is generally separated from the fuel pump either by a greater or lesser distance. This delivery valve has a special duty to perform upon interruption of the fuel pump pressure stroke, as the overflow 10 of the compression or explosion pressure from the cylinder into the suction part of the fuel pump must be avoided; otherwise the engine is put out of service. But it must be taken 15 into consideration that even with the very best workmanship and most careful attention, there is always the possibility that this valve might suddenly become defective and cause interruption in working, which is especially annoying with non-stationary motors 20 because it causes great inconvenience to reset the valve while the vehicle carrying the motor is in use upon the track or road, and in addition occupies too much time. With marine motors, the conditions are similar, as 25 a stop must be avoided. In this invention, it has been endeavoured to construct the valve in such a way that the valve and its seating can be easily taken out of the valve casing and can be replaced by spare parts which are 30 perfectly ground and ready for use. This is achieved by having the body of the valve seating readily removable and interchangeable in a sleeve which is connected with the fuel pump and guided in a bore of the valve 35 casing and detachable with the latter. As compared with the hitherto known valves, this construction has the further advantage that only the valve seating and the valve cone 40 as a unit must be manufactured of high class material, which therefore reduces the cost of the whole valve.

An embodiment of the invention is shown, in the drawing, in which,

Fig. 1 is a vertical sectional view of a valve structure embodying this invention; and

Fig. 2 is a fragmentary reduced view in the nature of an elevation of an engine having a valve structure such as shown in Fig. 1 included in the piping leading from the fuel pump to the engine cylinders.

The valve seating "a" is fitted loosely into the cylindrical bore of the sleeve "c" which is arranged in a piping "b" connecting the fuel pump "m" to the cylinders "n". The sleeve "c" fits loosely into the cylindrical bore 55 of the valve casing "d" and is connected with this by a screw cap "e". The body of the valve seat "a" is made oil-tight by means of packing rings "f", which are fitted on both sides of a flange "a¹" on the body of the valve seating and are compressed by the sleeve "c", when the screw cap "e" is tightened to effect 60 operative connection. The valve "g" is guided in the valve bore "h" and kept on its seating by a spiral spring "i". "j" and "k" are two 65 delivery pipes leading from the valve casing to the injection nozzles of the cylinders.

The under part of the bore "h" of the valve seating is fork shaped, and is in connection with a circular channel "l" of the valve body, which is defined by the rims "l¹" and "l²" which together with the inner bore of the sleeve "c" serve as a strainer for the fuel. 70

In order to replace a damaged valve, the screw cap "e" is loosened and unscrewed from the valve casing "d", then the sleeve "c" with the valve seating "a", and the valve "g" are withdrawn from the valve casing "d" by bending the pipe "b" and the valve seat with valve "g" therein may be readily and quickly removed and exchanged for another valve seating and valve unit, which may be as readily inserted in place after which the screw cap "e" may be screwed back upon the member "d" to connect the parts again in operative 80 connection. 85

Having now described and ascertained the nature of my said invention, I declare that what I claim is:

1. A delivery valve structure adapted for connection in the injection piping of an internal combustion engine and constructed for ready assembly or disassembly in the making of replacements of the valve seat and valve, 90 comprising a pair of complementary members adapted to be connected together and each adapted to be connected to a portion of said injection piping to be supported thereby, a valve seat member removably mounted be- 95 100

tween said complementary members, and a valve within said valve seat member.

2. A delivery valve structure adapted for connection in the injection piping of an internal combustion engine and constructed for ready assembly or disassembling in the making of replacements of the valve seat and valve, comprising a sleeve adapted for connection to the injection piping, a valve seat member slidably and removably mounted within the bore of said sleeve and having a bore in the valve seating forked near one end, a valve within the valve seat member, said valve seat member having a lip therearound and a groove in the said member adjacent said lip and in communication with the forked portion of the said bore, said lip being spaced from the wall of the bore of the said sleeve to form a filter for the fuel passing from the piping through the bore of the said sleeve into the forked portion of the bore of the valve seat member.

3. A delivery valve structure adapted for connection to the injection piping of an internal combustion engine and constructed for ready assembly or disassembling in the making of replacements of the valve seat and valve, comprising a valve casing member having a bore therein, a sleeve removably mounted within the bore of said valve casing member, said sleeve having a bore therein, a valve seat member removably mounted within the bore of said sleeve, a valve associated with said valve seat member, and detachable means for clamping the sleeve member within the valve casing member for detachably coupling the whole in assembled relation to provide a readily detachable oil-tight construction.

40 4. A delivery valve structure adapted for connection to the injection piping of an internal combustion engine and constructed for ready assembly or disassembling in the making of replacements and the like of the valve seat and valve, comprising a valve casing member having a bore therein, said valve casing member being adapted for connection to one portion of the injection piping, a sleeve slidably and removably mounted within the bore of said valve casing member, and having a bore therein connected to and in alignment with the bore of the valve casing member, said sleeve being adapted for connection to another portion of the injection piping, a valve seat member slidably and removably mounted within the two said aligned bores, a valve mounted within said valve seat member, and detachable means for connecting the valve casing member and the sleeve together to clamp the valve seat member and valve mounted therein in operative position.

5. A readily attachable and detachable delivery valve structure adapted for connection to the injection piping of an internal combustion engine, comprising a valve seat

and valve unit composed of high-class material, an enclosing structure including a pair of telescopic members not subject to wear during operation composed of lower-grade material, and means for detachably clamping said valve seat and valve unit in operative position within said enclosing structure.

6. In an internal combustion engine of the character described, and in combination, a cylinder, a fuel pump, a delivery valve housing including separable readily detachable parts, a pipe connecting said pump with one of the parts of said valve housing, a pipe connecting another of said parts of said valve housing with said cylinder, and a removable delivery valve seat and delivery valve operatively positioned within said valve housing.

7. Apparatus of the character described, comprising in combination, a cylinder of an internal combustion engine, a fuel pump feeding the cylinder, injection piping leading from the fuel pump to the cylinder, a valve fitting including separable readily detachable parts interposed intermediate the ends of the piping and supported thereby, and a delivery valve within said fitting for controlling the flow through said piping.

8. In a multi-cylinder internal combustion engine of the character described, and in combination, a fuel pump feeding a plurality of cylinders, piping leading from the fuel pump to the cylinders, a single delivery valve in said injection piping controlling the flow through said piping, and a valve fitting for the delivery valve comprising interfitting parts slidably mounted one within the other, one of said parts being connected to the fuel pipe from the pump, the other of said parts being connected to a plurality of fuel pipes each leading to one of the plurality of cylinders, a removable valve seating carrying the delivery valve removably mounted within said interfitting parts, and means for detachably coupling the said interfitting parts in assembled relation to provide a readily assembled oil-tight construction.

9. In an internal combustion engine of the character described, the combination with a cylinder; of a fuel pump feeding the cylinder, an injection piping leading from the pump to the cylinder, a delivery valve controlling the flow through the piping, and a fitting in said piping providing both a valve fitting for the delivery valve and a filter for the fuel passing through the injection piping to the cylinder.

10. In a multi-cylinder internal combustion engine of the character described, and in combination, a fuel pump feeding a plurality of cylinders, a delivery valve housing including separable readily detachable parts, a pipe connecting said pump with said valve housing, piping connecting said valve housing to a plurality of cylinders, and a single delivery valve seat and delivery valve removably

mounted within said detachable valve housing for controlling flow through the piping to the plurality of cylinders.

11. A delivery valve structure adapted for connection in the injection piping of an internal combustion engine for controlling the flow through the piping, comprising a fitting in said piping including detachably coupled interfitting parts, a removable valve seating carrying the delivery valve contained within said interfitting parts, one end of the valve seating remote from the valve being provided with ribs and an intervening groove which together with the inner wall of one of the enclosing parts form a filter for the fuel passing through the piping.

12. For use with an internal combustion engine of the character described, a delivery valve structure for controlling the flow of fuel to the engine, comprising a fitting formed of detachably coupled interfitting parts, a removable valve seating carrying a delivery valve enclosed within said interfitting parts, the valve seating cooperating with the inner wall of one of the enclosing parts to provide an annular restricted passage serving to filter the fuel passing through the piping.

13. A delivery valve structure adapted for connection in the injection piping of an internal combustion engine and constructed for ready assembly and disassembly in the making of replacements of the valve seat and valve, comprising a valve casing member having a bore therein and adapted for connection to one portion of the injection piping, a sleeve adapted for connection to another portion of the injection piping and slidably and removably mounted within the bore of said valve casing member, said sleeve having a bore therein in alignment with the bore of said valve casing member, a valve seat member slidably and removably mounted within the said aligned bores, a valve mounted within the valve seat member, a flange on said valve seat member slidably engaging the valve casing member beyond the end of said sleeve, packing means positioned on both sides of said flange, and detachable coupling means for fastening the interfitting parts together to compress the packing to form a readily assembled oil-tight construction.

In testimony whereof I have affixed my signature.

JOHANN MAHLER.
